CLAIM

The ornamental design for a rattle device, as shown and described.

DESCRIPTION

FIG. 1 is a front perspective view of an embodiment of a rattle device according to my new and ornamental design;

FIG. 2 is another front perspective view thereof;

FIG. 3 is a front elevation view thereof, wherein the rear elevation view thereof is identical;

FIG. 4 is a left side elevation view thereof, wherein the right side elevation view thereof is identical;

FIG. 5 is a top plan view thereof; and,

FIG. 6 is a bottom plan view thereof.

The evenly-spaced broken lines depict portions of the rattle device that form no part of the claimed design. The embodiment of the rattle device depicted in the Figures can be used in the field of fishing, and in certain non-limiting examples, the rattle device is coupled to fishing lines or fishing lures.
